UNITED STATES PATENT OFFICE.

JAMES M. MACDONALD, OF EAST ORANGE, NEW JERSEY.

CONTAINER.

Application filed March 20, 1926. Serial No. 96,149.

My invention relates to containers and refers particularly to containers suitable for powders to be applied by means of powder puffs.

5 One of the essential elements of a practical face powder container is that of size, for it is evident that a container of this character must be as small as is possible consistent with the uses to which it is applied.

10 Notwithstanding that it is generally admitted that loose face powder is more efficient and valuable than powder compacts, the latter have largely replaced the former because of the difficulties and inconveniences incident to the use of loose powder as compared with compacts.

The chief difficulties presenting themselves in the production of a loose powder container are those incident to devising one which will 20 be of minimum size and which will prevent the sifting or spilling of the powder during use, such sifting being highly disadvantageous as it is liable to injure the gown of the user.

25 My invention overcomes these objectionable features and presents a loose powder container which is small in size and which will allow of the use and application of the container powder without danger of its sifting during the carriage of the container or of its being spilled during its application.

The above described, and other, valuable features of my device will be evident upon a consideration of this specification and its accompanying drawings.

In the accompanying drawings illustrating one form of the device of my invention similar parts are designated by similar numerals.

40 Figure 1 is a top plan view of one form of the device of my invention.

Figure 2 is an edge view of Figure 1.

Figure 3 is a plan view of the device of Figure 1 in open position, partly broken away for purposes of explanation.

Figure 4 is an enlarged cross-section through the line 4—4 of Figure 1.

Figure 5 is a top view of one of the upper members of Figure 4.

50 Figure 6 is a top view of the ring-shaped supporting member of Figure 4.

Figure 7 is a top view of the bottom member of Figure 4.

The particular form of the device of my invention shown in the accompanying drawings comprises an annular bottom 10 the

edge of which is turned inwardly upon itself 11 and then upwardly 12.

Positioned within the bottom member is a ring-shaped supporting member 13, the outer 60 edge of which is turned downwardly 14 and then outwardly 15, the ring member being affixed to the bottom member by solder, or otherwise. The inner edge of the ring member is turned downwardly and inwardly 65 forming the shoulder 16 and then downwardly 17.

Positioned within the ring member is a grid member 18 having a plurality of openings 19, 19 therein. The outer edge of the grid member 18 is turned downwardly and inwardly, thus forming an inverted shoulder 20, and then downwardly 21. The members 21 and 17 are affixed together by solder, or otherwise. 70

It will thus be seen that the bottom, the ring supporting member and the grid are attached to each other to form a bottom member, or container. Positioned above the container, and revoluble thereon is an annular 80 member 22 which is turned inwardly 23, then downwardly and then inwardly, forming the shoulder 24, the two shoulders 20 and 16 thus act as guides and retaining means for the member 22 during its revolution. 85

A cover, or lid, 25 is hingedly attached to the member 22 at 26. Hingedly attached to the cover 25 at 27 is a catch 28, capable of closing attachment with the lip 29 carried by the member 22. 90

An annular bezel 30 retains the mirror 31 within the cover 25.

Powder 32 is placed within the bottom receptacle 33 and a powder puff 34 is placed upon the grid 18. 95

The operation of the device is as follows:—The device in closed position, as shown in Figure 4, is inverted in order that the powder 32 may fall against the grid 18 and thus be impinged upon the puff 34 100 through the openings 19, 19 of the grid. The bottom member, or receptacle, is then held in one hand and the upper members in the other hand and the two members are given a revoluble movement with respect to each other. As the puff 34 is held in tight abutment against the grid 18 by the mirror 31, and as the edges of the puff are held in tight abutment against the member 23 by the bezel 30, the only powder which can escape from 105 the receptacle is that portion which escapes through the openings 19, 19 against the puff 110

31, and as the puff revolves with respect to the grid, only a small portion of the powder will be distributed evenly over the puff surface. It will be further noted that as the 5 grid is in pressure abutment against the puff, the powder will be forced into the puff sufficiently to prevent it from dropping therefrom when the puff is removed from the device preparatory to application to the face. 10 The device is then reversed to upright position, the catch 28 released and the lid, or cover, 25 opened, thus exposing the puff 34.

It will thus be seen, that my invention comprises a powder container in which the 15 powder may be distributed upon a powder puff, by the revolution of the device elements, the puff acting as a preventative for the escape of excess powder therefrom.

I do not limit myself to the particular 20 size, shape, number or arrangement of parts as shown and described as these are given simply as a means for clearly describing my invention.

What I claim is:—

- 25 1. In a loose powder container, in combination, a bottom powder receptacle, a grid top attached to said receptacle, an upper member spaced from the grid and revoluble thereabove and a hinged cover carried by the revoluble member.
2. In a loose powder container, in combination, a bottom powder receptacle, a grid top attached to said receptacle, an upper member spaced from the grid and revoluble 35 thereabove, a hinged cover carried by the revoluble member and means whereby the closing of the cover will cause compressed abutment between the bottom grid and a powder puff placed thereon.
- 40 3. In a loose powder container, in combination, a bottom powder receptacle, a grid top to said receptacle, an annular upwardly extended flange carried by, and revoluble upon, the bottom member, and a cover for 45 the compartment formed by the flange.
4. In a loose powder container, in combination, a bottom powder receptacle, a grid top to said receptacle, an annular upwardly extended flange carried by and revoluble 50 upon the bottom member, a cover for the compartment formed by the flange and downwardly extended means carried by the

cover and within the flange when the cover is closed.

5. In a loose powder container, in combination, a bottom powder receptacle, a grid top to said receptacle, an annular upwardly extended flange carried by and revoluble upon the bottom member, a cover for the compartment formed by the flange, downwardly extended means carried by the cover and within the flange when the cover is closed and means for locking the cover in closed position without preventing the revolution of the revoluble member and the bottom member.

6. In a loose powder container, in combination, a bottom powder receptacle, a grid top to said receptacle, an annular upwardly extended flange carried by and revoluble 70 upon the bottom member, a cover for the compartment formed by the flange forming a puff receptacle between the cover and the grid and means carried by the cover and the flange for locking the cover in closed position.

7. In a loose powder container, in combination, a bottom powder receptacle, a grid top to said receptacle, an annular upwardly extended flange carried by and revoluble 80 upon the bottom member, a cover forming a puff receptacle with the flange and the grid, a downwardly extended peripheral member carried by the cover and within the flange when the cover is closed and means carried 85 by the cover and the flange for locking the cover in closed position.

8. In a loose powder container, in combination, a bottom powder receptacle, a grid top to said receptacle, an annular upwardly 90 extended flange carried by and revoluble upon the bottom member, a cover forming a puff receptacle with the flange and the grid, a downwardly extended peripheral member carried by the cover and within the flange 95 when the cover is closed, means carried by the cover and the flange for locking the cover in closed position and a mirror carried upon the inner face of the cover.

Signed at New York city in the county of 100 New York and State of New York this 19th day of March, 1926.

JAMES M. MACDONALD.
